UNITED STATES PATENT OFFICE.

WILLIAM J. BOLTON, OF DETROIT, MICHIGAN.

FURNACE.

SPECIFICATION forming part of Letters Patent No. 783,815, dated February 28, 1905.

Application filed July 11, 1904. Serial No. 216,194.

To all whom it may concern:

Be it known that I, WILLIAM J. BOLTON, a subject of the King of Great Britain, residing at Detroit, county of Wayne, State of Michigan, have invented a certain new and useful Improvement in Furnaces; and I declare the following to be a full, clear, and exact description of the invention, such as will enable others skilled in the art to which it pertains to make and use the same, reference being had to the accompanying drawings, which form a part of this specification.

This invention relates to furnaces.

It has for its object an improved furnace construction in which provision is made to direct highly-heated air from directly over the fire-pot into any one of the heat-conducting flues through which it may be desired to conduct an extra amount of heat.

In the drawings, Figure 1 is a vertical section of the furnace. Fig. 2 is a horizontal section through the auxiliary heating-drum A. Fig. 3 indicates the means for turning the conductor which leads from the auxiliary heating-drum. Fig. 4 shows the dial which indicates the direction to which the outlet of the auxiliary pipe is directed.

1 indicates the fire-pot of a furnace, over which is a combustion-chamber 2, from which the products of combustion pass to a radiating-drum 3, provided with baffle-plates or circular partition-walls which compel the heated gases to traverse the entire circuit of the outer wall of the heating-drum 3 before escaping through the smoke-flue 4 to the chimney.

The fire-pot and combustion-chamber and a part of the smoke-flue and the heating-drum are all inclosed in a casing 5, from the top of which lead the several hot-air ducts 6. An auxiliary heating-drum A hangs in the combustion-chamber 2 and is provided with a cold-air-inlet flue 7 and hot-air duct 8. The cold-air flue leads into the side of the heating-drum, and the hot-air duct leads out of the center and directly upward through the drum 3. The hot-air duct 8 is provided with an elbow and with a horizontal duct 9, which turns with the elbow on the vertical duct 8 to shift the mouth 9^a of the hot-air duct to register with the inlet to any one of the hot-air flues 6. The el-

bow 8^a is provided with a pivot-rod 10, that extends upward through the top of the casing 5 and, if necessary, through the floor of the building in which the furnace is located and terminates with a hand-wheel 12, by means of which the horizontal portion 9 of the hot-air flue may be rotated from the room above the furnace. A pointer 13 indicates on a dial 14 the direction of the horizontal part 9, and on the dial are also indicating-marks to designate the location of the inlets to the flues 6. By the use of this rotatable pipe, which leads directly from a highly-heated drum that is in the combustion-chamber and immediately over the fire-pot, the warmest air of the furnace may be sent directly through any one of the air-ducts to any portion of the building and that part of the building which is for the time being subjected to winds or which for other reasons is lower in temperature than it should be may be warmed by furnishing it with the warmest air produced in the furnace. The drum A is provided with baffle-plates 15 and 16, which compel the cold air entering through the cold-air flue 7 to travel entirely around the outer circuit of the drum before entering the inner chamber and the mouth of the vertical duct 8. The rod 10, which is employed to turn the horizontal part 9 of the hot-air duct, is preferably seated on a foot-plate in the drum A and preferably braced at the mouth of the elbow 8^a by braces 17.

What I claim is—

1. In combination with a furnace, an auxiliary heating-drum located therewithin, a heat-duct leading therefrom and adapted to connect with conductor-pipes, and means for shifting said heat-duct from connection with one to similar position with regard to another, substantially as described.

2. In combination with a furnace provided with a casing and an inclosed heat-chamber, hot-air ducts leading from the heat-chamber, an auxiliary heating-drum located in the combustion-chamber of the furnace, a cold-air duct leading thereto, a duct leading from said auxiliary heating-drum rotatable on an axis and adapted to be turned to register with any one of the several hot-air ducts, substantially as described.

3. In combination with a furnace provided with a fire-pot, a combustion-chamber, a casting inclosing said chamber and spaced therefrom, an auxiliary heating-drum located in 5 said combustion-chamber, a cold-air-inlet flue leading thereto from without, a hot-air duct rising from said drum adapted to register with any one of several hot-air ducts surrounding its free end and means for turning said duct

from one to another of said surrounding ducts, substantially as described.

In testimony whereof I sign this specification in the presence of two witnesses.

WILLIAM J. BOLTON.
